UNITED STATES PATENT OFFICE.

CHARLES C. HANSON AND JOHN TWARDOWSKY, OF CHICAGO, ILLINOIS, ASSIGNEES,
BY MESNE ASSIGNMENTS, TO UNIVERSE CORPORATION, OF CHICAGO, ILLINOIS, A
CORPORATION OF ILLINOIS.

COMPRESSOR.

Application filed May 31, 1921. Serial No. 473,781.

To all whom it may concern:

Be it known that we, CHARLES C. HANSON, a citizen of the United States, and JOHN TWARDOWSKY, a citizen of Russia, both residing at Chicago, in the county of Cook and State of Illinois, have invented certain new and useful Improvements in a Compressor; and we do hereby declare the following to be a full, clear, and exact 10 description of the invention, such as will enable others skilled in the art to which it appertains to make and use the same.

Our invention relates to fluid compressors, its general objects being those of providing 15 simple and effective means for separating lubricating oil from the compressed fluid and for delivering the separated oil to the chamber from which the lubricating oil is supplied.

20 In operating many types of compressors, such as those forming portions of mechanical refrigerating outfits for household or store use, it is highly desirable that automatically operated means should be provided for lubricating the compressor, so as to obviate the necessity of having skilled attendants or of depending on the users for attending to the lubrication. To insure an ample supply of the lubricant for long 25 periods of time, it is desirable in such cases to take the lubricant from an oil reservoir of large capacity, and in practice a lubrication adequate for reducing the friction to a minimum and for preventing a wearing of the 30 parts can only be obtained by supplying an excess of the oil to these moving parts. Consequently, some of this excess is apt to be mixed with the compressed fluid and discharged with the latter into parts of the 35 refrigerating system where the presence of the lubricant may interfere with the expansion valve and may otherwise be highly undesirable.

40 For example, with a piston and cylinder type of compressor such as the one resulted in our copending application No. 469,110, filed May 13, 1921, on a compressor, we have shown a compressor in which the piston is continuously lubricated by oil stored in the 45 crank casing and splashed out of the latter by the crank and the pitman when the compressor is in operation. With such an arrangement, a portion of the fluid will tend to leak through between the piston and the 50 cylinder during the compression period of

each cycle of operation and will therefore enter the crank casing, so that it is necessary to have this crank casing substantially sealed to avoid a leakage of the fluid through the same, as such leakage not only would mean 60 a gradual loss of the charge of fluid but would also be objectionable owing to the poisonous nature of the compressible fluids commonly used in mechanical refrigerating systems. This sealing of the crank chamber 65 causes the leakage of compressed fluid into the same to raise the pressure within the chamber, thereby introducing a back pressure which will resist the tendency of the fluid within the cylinder from forcing the 70 thin film of oil which surrounds the piston back into the crank chamber. Consequently, some of this oil will be expelled with the compressed fluid into the discharge passage of the compressor. If this oil is left intermingled with the compressed fluid, its 75 lighter specific gravity will cause it to float upon the subsequently liquefied fluid, thereby interfering with the proper action of the expansion valve to an extent which will gradually increase as the proportion of oil is increased during the continuous operation of the compressor.

Our invention aims to overcome such as this and other possible difficulties by providing means for automatically separating the oil from the fluid after the latter has been compressed and before this fluid is delivered to the expansion valve of the system. It also aims to provide simple means for returning the separated oil to the oil reservoir (which in the above mentioned instance would be the crank casing) and aims to employ the pressure of the compressed fluid for this purpose without having the fluid itself 85 follow into the oil reservoir. Moreover, our invention aims to employ an exceedingly simple and inexpensive arrangement for this purpose, aims to utilize the usual compressing mechanism of the compressor for 90 automatically opening and closing the oil return connection at the right periods. It also aims to provide simple and effective means for adjusting the rate at which the oil is returned, so that this returning may be 95 properly proportioned to the rate at which oil was carried through the compressing chamber. Moreover, our invention aims to provide an exceedingly simple, compact and inexpensive construction for this general 105 110

purpose, and one which does not involve any parts likely to get out of order. Still further and more detailed objects will appear from the following specification and from the accompanying drawings, in which—

Fig. 1 is a central and vertical section through a fluid compressor equipped with the oil separating means of our invention.

Fig. 2 is a section taken through the upper portion of Fig. 1 axially of the cylinder and at right angles to Fig. 1.

Fig. 3 is a transverse section through the oil separating chamber, taken along the correspondingly numbered line in Fig. 1.

15 In the embodiment of the drawings, we are showing a compressor including a cylinder 1 having a lateral fluid inlet 2 intermediate of its ends, so that the piston 3 acts as its own valve for controlling the admission 20 of the fluid to the cylinder. We are also showing the compressor as having a movable cylinder head 4 mounted for a slight movement longitudinally of the cylinder within a storage chamber 5 from which the compressed 25 fluid is gradually discharged through an outlet 6 in an annular boss 7 which forms a stop for limiting the movement of the cylinder head 4 away from the cylinder proper.

Instead of having the outlet 6 lead directly 30 to the piping 8 of the refrigerating system in connection with which the compressor is used, we interpose between these a chamber 9 of considerably larger bore and desirably extending for some distance below the outlet 35 pipe 8. Mounted within the chamber 9 are a series of baffles, each of which is here shown as comprising a sheet metal disk 10 having a series of downwardly directed tongues 11 bent at an acute angle from the plane of the disk, so that these tongues will be interposed 40 in the path of the fluid passing through the openings formed by bending the tongues out of the plane of the disk from which they were formed. With the baffles thus arranged, 45 the particles of oil carried over into the chamber 9 with the compressed fluid will be caught upon these baffles and will drip into the bottom of the chamber.

Each of the baffles desirably has a lower 50 edge portion cut away as shown in Fig. 3 so as to permit the accumulating oil 12 to flow freely along the bottom of the chamber 9 into an oil return duct 13, which duct is desirably formed in the adjacent wall of the compressor cylinder. This duct 13 is connected to the bore of the cylinder by a port 55 14 which is so located that it is covered by the piston 3 during almost the entire reciprocation of the latter, being only opened at the bottom of this piston when the piston is 60 at the extreme end of its compression stroke as shown in Fig. 2, or in other words at the time when the compressed fluid is being discharged from the cylinder into the storage 65 chamber 5. When the piston reaches this

point, the port 14 is uncovered and the pressure of the fluid in the chamber 9 forces oil from the return duct 13 through the port 14 into the cylinder below the piston, thereby returning the oil to the crank chamber which forms the oil reservoir. If this forcing of the oil through the port 14 were unduly rapid, all of the oil which had accumulated in the duct 13 and the chamber 9 might be returned in this manner to the crank casing 70 and some of the compressed fluid might then follow into the latter also. To avoid this, we provide suitable means for throttling the returning of the oil, as for example by using a needle valve 15 threaded into the wall of the cylinder adjacent to the juncture of the duct 13 with the port 14, this needle valve being accessible when a suitably packed cap screw 16 is removed. By properly adjusting the valve 15 we can readily throttle the returning of the oil to an extent proportioned 75 to the rate at which the oil is being carried over into the oil-separating chamber 9, thereby continuously maintaining such a supply of oil in the duct 13 (and possibly in the bottom of the chamber 9 also) as will seal the said oil return passages against having the compressed fluid follow the oil into the lower portion of the cylinder and hence 80 into the crank casing.

To increase the effectiveness of the baffles, we desirably arrange these with the openings and tongues on consecutive baffles in staggered relation, thereby compelling the fluid to follow a zigzag course through the chamber 9 and effectively insuring the desired separation of oil from the fluid before it reaches the outlet pipe 8. We also desirably interpose a fluid storage chamber (such as the chamber 5) between the compression chamber (or cylinder) and the part of the discharge passage in which the baffles are located. By making this storage chamber of considerably larger cross-section than its connection to the said discharge passage 100 part 9 we cause the compressed fluid to flow at a retarded speed past the baffles and hence avoid having an unduly fast rush of the fluid carry oil particles with the same into the piping 8. Moreover, we desirably form the chamber 9 within the same casting which affords the stop 7 for the movable head of the cylinder and which has the fluid storage chamber 5 formed in it, thereby greatly 105 simplifying and cheapening the construction.

However, while we have illustrated and described our invention in a highly desirable embodiment including a certain arrangement of the baffle plates which form the oil separating means and including a throttling valve of a pointed screw type, we do not wish to be limited to these or other details of the construction and arrangement here disclosed, it being obvious that various 110 115 120 125

modifications might be made without departing from the spirit of our invention or from the appended claims. Neither do we wish to be limited to the use of our invention in connection with a refrigerator system or in connection with a movable piston head construction and an oil leak deterring groove 17 after the manner of our said pending application, although we have 5 found that the oil separating and returning means of our invention are adequate for separating and returning the somewhat larger amount of oil which may be carried over with the compressed fluid when the 10 cylinder is equipped with a fluid-leak deterring groove 17 after the manner described in our said companion application.

We claim as our invention:

1. In a compressor and in combination, 20 an oil reservoir, oil-separating means in the discharge passage of the compressor, and oil return means operatively connecting the oil-separating means automatically with the oil reservoir only during the discharge of 25 compressed fluid from the compression chamber.

2. In a compressor and in combination, an oil reservoir, oil-separating means in the discharge passage of the compressor, oil return means interposed between the oil-separating means and the oil reservoir and arranged for automatically connecting the oil-separating means with the oil-reservoir only 30 during the discharge of compressed fluid 35 from the compression chamber, and adjustable means for throttling the said oil return means.

3. In a fluid compressor and in combination, oil-separating means in the discharge 40 of the compressor, an oil reservoir, and throttled oil return means automatically connecting the oil-separating means with the oil reservoir during the discharge of fluid from the compression chamber, the 45 said return means being operatively disconnected during the remainder of each cycle of operation of the compressor.

4. In combination, a fluid compressor, an oil-separating chamber through which the 50 compressed fluid is discharged, an oil reservoir, means within the said chamber for separating oil from the compressed fluid, a duct leading from the said chamber to the oil reservoir, and automatically operating 55 means for effectively opening the duct only coincidental with the discharge of compressed fluid from the compression chamber.

5. In combination, a fluid compressor, an oil-separating chamber through which the 60 compressed fluid is discharged, an oil reservoir, means within the said chamber for separating oil from the compressed fluid, a duct leading from the said chamber to the oil reservoir, automatically operating means for 65 effectively opening the duct only at the time

of the discharge of compressed fluid from the compression chamber, and adjustable means for throttling the said duct.

6. The combination with a fluid compressor 70 of the piston and cylinder type, of an oil-separating chamber through which the compressed fluid is discharged, means within the chamber for separating oil from the compressed fluid, and an oil return duct leading from the said chamber to the cylinder and 75 so connected to the latter as to have its connection automatically uncovered by the piston only when the piston is at the end of its fluid compressing stroke.

7. The combination with a fluid compressor, 80 of an oil reservoir arranged for supplying lubricant thereto, an oil-separating chamber disposed above the oil reservoir and through which the compressed fluid is 85 discharged, means within the chamber for separating oil from the compressed fluid, and an oil return duct leading from the bottom of the oil-separating chamber to the oil reservoir and so connected to the latter as 90 to have its connection automatically opened only at the extreme intake time of the compressor.

8. The combination with a fluid compressor of the piston and cylinder type having 95 a supply of lubricating oil in the crank case thereof, of an oil-separating chamber disposed above the said crank case, means within the said chamber for separating oil from the compressed fluid, and an oil return duct leading from the bottom of the 100 chamber into the cylinder at a point disposed between the piston and the crank case when the piston is at the end of its compression stroke.

9. The combination with a fluid compressor of the piston and cylinder type having 105 a supply of lubricating oil in the crank case thereof, of an oil-separating chamber disposed above the said crank case, means within the said chamber for separating oil 110 from the compressed fluid, an oil return duct leading from the bottom of the chamber into the cylinder at a point disposed between the piston and the crank case when the piston is at the end of its compression stroke, 115 and an adjustable valve arranged for throttling the said duct.

10. In a fluid compressor and in combination, a cylinder having a discharge outlet at its upper end, a piston slidable therein, 120 a crank case opening into the lower end of the cylinder and serving also as a lubricant reservoir, an oil-separator disposed above the lowermost point reached by the piston and disposed in the path of the fluid compressed by the cylinder and discharged through the said outlet, and an oil return duct connecting the bottom of the oil reservoir to the bore of the cylinder just below 125 the point reached by the lower end of the 130

piston when the piston is at the top of its stroke.

11. In a fluid compressor and in combination, an oil reservoir, oil-separating means disposed in the discharge passage of the compressor, means actuated by the pressure of the compressed fluid adjacent to the oil-separating means for returning separated oil to the oil reservoir, and a compression

chamber interposed between the compressor 10 and the oil-separating means and having a restricted opening towards the latter so as to reduce the speed with which the compressed fluid passes the oil-separating means.
